(57) **CLAIM**

The ornamental design for a charging station for a portable illumination assembly, as shown and described.

DESCRIPTION

FIG. 1 is a top perspective view of a charging station for a portable illumination assembly, illustrating our new design; FIG. 2 is a front side view thereof;

FIG. 3 is a left side view thereof, depicting in phantom, an illumination assembly shown as partially attached therewith in a use condition thereof, the right side view of the charging station being a mirror image thereof;

FIG. 4 is a top plan view thereof;

FIG. 5 is a bottom view thereof; and,

FIG. 6 is a rear side view thereof.

The broken line showing is included for the purpose of illustrating environmental features and forms no part of the claimed design.
